UNITED STATES PATENT OFFICE.

GILBERT E. JONES, OF NEW YORK, N. Y.

GALLEY.

SPECIFICATION forming part of Letters Patent No. 365,308, dated June 21, 1887.

Application filed October 28, 1886. Serial No. 217,458. (No model.)

To all whom it may concern:

Be it known that I, GILBERT E. JONES, a citizen of the United States, residing at New York, in the county and State of New York, have invented new and useful Improvements in Galleys, of which the following is a specification.

This invention relates to improvements in galleys; and it consists in the features set forth in the following specification and claims, and illustrated in the accompanying drawings, in which—

Figure 1 is a plan view of a galley containing my invention. Fig. 2 is a section in the plane $x-x$, Fig. 1. Fig. 3 is a section in the plane $y-y$, Fig. 1. Fig. 4 is a plan view of a quoins, the cam being indicated in dotted outlines. Fig. 5 is a section in the plane $z-z$, Fig. 4. Figs. 6, 7, and 8 show modified forms of locking-block and side-stick.

Similar letters indicate corresponding parts.

In the example shown in the drawings, the letter A indicates the side of a galley.

B indicates the type or matter.

25 C indicates the side-stick.

G is a quoins, which may be provided with a side lock, D, and an end lock, E. The quoins G and its cam F are supported on a pivot, I, and the cam is provided with lugs H H, for 30 attachment of a wrench, through which the cam, quoins, and locks D E are actuated. The side lock, D, presses against the side-stick C to lock up the matter. The end lock, E, is adapted to lock against the end of the matter. 35 The end lock, E, is ridged or arched, so that it can pass over the side-stick C.

Heretofore it has been customary to apply two or more quoins along the side-stick C to lock up the matter, but such application of 40 several quoins consumes time.

To avoid the application of several quoins, I have provided the galley with a locking-block, N. The locking-block N may consist of wood, lead, or other suitable material. It 45 is well to fasten said locking-block to the galley, so that said block N will not become detached or lost from the galley. When the type or matter has been placed in the galley and is ready to be locked up, the side-stick C 50 is forced in between the locking-block N and the matter, so as to lock up the matter. By

beveling or inclining the edges or part of the edges of the block N which the side-stick C passes the side-stick will be readily guided into place, and a slight blow or push upon the 55 side-stick with the hand or any suitable instrument will crowd or force the side-stick in between the block N and the matter B, so as to lock up the matter. By this means the application of at least one quoins and the time 60 required for such application are saved. I may even, if desired, avoid the use of any quoins and apply two or more locking-blocks in the manner shown in the application of the block N in the drawings. In such case it will only 65 be necessary to crowd or force the side-stick into its proper place, whereby the matter will become locked up, the time required for the application of a quoins or quoins being saved.

The locking-block N may be screwed, soldered, or otherwise secured or fixed to the galley.

In order to prevent endwise or longitudinal motion of the side-stick C, said side-stick may be attached to the locking-block N. A convenient manner of attachment is shown in 75 Figs. 6, 7, and 8, where the side-stick is provided with a recess or notch, O, adapted to engage a lug or projection, P, on the locking-block N.

The side-stick may be provided with notches O near either of its ends, so that either end of the side-stick may engage the lug P. As seen in the drawings, the form of lug P and notch O is such as to allow a ready insertion or withdrawal of the side-stick into or from the galley.

By inclining a face of the lug P, as seen in Fig. 6, the side-stick can be readily put into or taken out of engagement with the locking-block N, while the side-stick when in engagement with the locking-block N is held against endwise or longitudinal motion. Of course the same engagement can be obtained by forming the lug P on the side-stick and the notch O in the locking-block.

I do not herein claim a quoins provided with a cam having a rigidly-attached handle or lugs by which to turn it; and, further, I do not herein claim a quoins provided with a stop to co-operate with a stop on a rotating cam 100 journaled on the quoins in such manner that when the cam is turned to bring its stop into

engagement with the stop on the quoin the latter, with the cam, can be introduced into or removed from the galley, as such features constitute the subject-matter of my application of 5 even date herewith, Serial No. 217,459.

What I claim as new, and desire to secure by Letters Patent, is—

1. A galley provided with a locking-block having a lug or projection, P, in combination with a side-stick having a notch, O, substantially as described.

2. A galley provided with a locking-block,

N, fixed in a stationary position and having a beveled or inclined edge, in combination with a side-stick and a quoin, substantially as described. 15

In testimony whereof I have hereunto set my hand and seal in the presence of two subscribing witnesses.

GILBERT E. JONES. [L. S.]
